UNITED STATES PATENT OFFICE.

WENDELL A. BARKER, OF CHICAGO, ILLINOIS, ASSIGNEE TO THOMAS ELEVATOR COMPANY, OF CHICAGO, ILLINOIS, A CORPORATION OF ILLINOIS.

ELECTRICALLY-DRIVEN HOIST.

1,141,679,

Specification of Letters Patent.

Patented June 1, 1915.

Application filed November 24, 1913. Serial No. 802,842.

To all whom it may concern:

Be it known that I, WENDELL A. BARKER, a citizen of the United States, residing at Chicago, in the county of Cook and State 5 of Illinois, have invented certain new and useful Improvements in Electrically-Driven Hoists, of which the following is a specification.

This invention relates to certain improvements in hoisting machines, and particularly to improvements in an electrically driven hoist.

The invention has reference particularly to the arrangement of the hoisting drums, 15 gears, and clutch mechanisms, with respect to a jack shaft to which the power is transmitted in the first place from the electric motor.

More particularly the invention has as 20 one of its primary objects the provision of such relationship between the various mechanisms or elements above mentioned that they may be brought together in an extremely simple manner and within a minimum of space and width of machine.

The invention also has for one of its important objects the provision of such a relationship between the above-mentioned mechanisms that the strains and stresses 30 occasioned by the sudden clutching or un-clutching of the hoisting drums will be safely and instantaneously taken up or compensated for by the resiliency of an element which may be designed or proportioned 35 with this object in view.

Other objects and uses will appear from a detailed description of the invention, which consists in the features of construction and combinations of parts hereinafter described 40 and claimed.

In the drawings:

Figure 1 shows a plan view of an assembled hoist embodying the features of my invention; Fig. 2 shows a side elevation 45 of the hoist of Fig. 1; Fig. 3 shows a horizontal section through the clutch ends of the hoisting drums; and Fig. 4 shows a detailed plan view of one of the drum shifting cam blocks.

50 In the particular embodiment of the invention which is disclosed in the drawings the hoist is provided with two drums 5 and 6. These drums are rotatably mounted or journalled on the shafts 7 and 8 which in turn are journalled in the frame 9. For this

purpose the frame may be conveniently constructed as a base portion 10 having the side standards 11 and 12 in which the shafts are journalled. Each shaft may be provided with a spool 13 to facilitate certain classes 60 of hoisting operations.

Driving gears 14 and 15 are rigidly secured to the shafts 7 and 8 respectively, so that as said gears are driven they will drive the shafts. Each gear in turn carries a 65 friction cone 16, and said cones are adapted to be engaged by the tapered recesses 17 of the hoisting drums when the drums are shifted endwise the necessary amount. When such engagement is effected the shifted drum will be driven by its gear through the medium of its friction clutch. In connection with this feature it is preferred that each of the main gears be mounted adjacent to the corresponding shaft bearing 70 of the standard 11, so that said bearing member will take up the end thrust occasioned in securing the frictional engagement.

I have provided a simple form of drum 80 shifting mechanism for bringing into action the friction clutch of each drum. In the particular arrangement illustrated a rotatable block or the like 18 is mounted between each drum and the corresponding 85 bearing of the standard 12. These rotatable blocks are provided with cam faces 19 which engage complementary faces 20 of the bearings, so that as each block 18 is swung through the desired angle it will 90 shift along the shaft on which it is mounted and thus carry its drum toward and against the corresponding friction cone 16. Each of the blocks 18 may be conveniently controlled by means of a handle 21 acting 95 through levers and linkages, as best shown in Fig. 2. These handles are preferably both located to one side of the hoist, as best shown in Fig. 1.

If desired, ratchet wheels 22 may be secured to the ends of the drums, and pawls or dogs 23 may be provided for engaging said ratchets to prevent a backward movement of the drums. In addition to the ratchets and pawls above described, friction 100 brake mechanism is illustrated as another convenient means of locking the drums against rotation. For this purpose the clutch end of each drum has its outer face 105 finished, and a brake band 24 is adapted to 110

work on such outer face. Shafts or rods 25, connected to these brake bands, extend through the lower portion of the hoist and carry the foot pedals 26, depression of each of which serves to tighten the corresponding brake band to set the brake. Helical springs 27 tend to rock the shafts 25 for the purpose of releasing the brake bands and raising the pedals. It is preferred that the foot 13 pedals 26 be mounted at the same side of the hoist as the handles 21 to facilitate control of the drums and other mechanism.

From the foregoing it will be seen that the drums and shafts are to be rotated by rotation of the gears 14 and 15. For this purpose a jack shaft 27^a is extended through the machine from side to side, being suitably journaled in the standards 11 and 12. At one end this jack shaft carries a pinion 28, meshing with both of the gears 14 and 15 to drive them both in the same direction. At its other end the jack shaft carries a sprocket wheel 29, which is preferably mounted in the same vertical plane, or in 25 alignment with, the drum shifting blocks 18. A motor 30 drives the jack shaft through the medium of a chain 31 which travels over the sprocket 29. Examination of Fig. 2 will show that the relative positions of the sprocket 30 29 and the motor sprocket are such that the chain travels beneath the drum shifting mechanism of the drum 5, and are such that said chain lies between the end of the drum and the standard 12. By thus arranging 35 or locating the parts the chain works or travels in a space which would otherwise be unoccupied, inasmuch as a certain amount of room is necessary to accommodate the drum shifting mechanisms. It therefore follows that with this arrangement no additional width of the hoist is necessary for the accommodation of the chain and sprockets over that which would be necessary under any circumstances for the accommodation 40 of the drums and drum shifting mechanisms. It therefore follows that there is a peculiar and definite relationship between the location of the chain and sprockets and the drum shifting mechanisms.

50 It will be appreciated that with the arrangement disclosed above the entire power for the operation of both of the hoisting drums 5 and 6, and for both of the spools 13, is always transmitted through substantially 55 the entire length of the jack shaft 27^a from the sprocket 29 to the pinion 28. The jack shaft and the main gears 14 and 15 travel continually as long as the motor is in operation, and regardless of whether or not the hoisting load on either drum or spool be continuous or intermittent. Therefore as the drums are successively or intermittently clutched and unclutched, or as hoisting loads are thrown onto or off from the spools, the 60 amount of driving force transmitted

through the jack shaft fluctuates through very wide and sudden extremes. These sudden and large fluctuations might be very detrimental to the power transmitting mechanisms unless some means were provided for instantaneously compensating to some extent for them. In the arrangement illustrated this compensation is afforded by reason of the length and torsional resiliency of the jack shaft.

70 It is well understood that the ability of the shaft to twist and absorb energy or shock in twisting is determined not only upon the material of which it is made and by its diameter, but also by its length between the point of application of the twisting forces. Therefore in the arrangement set forth herein the jack shaft possesses a maximum of torsional resiliency, that is, ability to twist between its ends and store 75 up energy within its material by reason of such twisting, ultimately giving up such energy as it untwists. This is for the reason that the maximum feasible length of jack shaft is afforded between twisting points by 80 placing the driving sprocket at one end and the pinion at the other.

85 It therefore follows that the relationship of parts disclosed herein is not only such as to accommodate the several elements or 90 mechanisms within a minimum of space, by having the driving sprocket lying in the same vertical plane as the drum shifting mechanisms, but that also the arrangement 95 at the same time provides a maximum of resiliency in the jack shaft for the reason above set forth.

100 It will be understood that although the storing up of energy in the jack shaft, and the subsequent delivery of energy from 105 the jack shaft by twisting and untwisting serves to provide a reservoir for energy for equalizing the strains and stresses on the gears and other parts, still it is not necessary that the shaft should twist or 110 untwist to a large extent in order to secure this equalizing effect. In other words, by using a material of high elasticity, such as steel of the desired characteristics, a com- 115 paratively large amount of energy per cubic inch can be stored up in the same without exceeding the safe elastic limit of the metal, and without an unduly large twist of one end of the jack shaft with respect to the other.

120 I wish also to emphasize the fact that the desirability of making provision for protection of the gears and other parts against abnormal strains and shocks is great in a machine of this kind in which the driving element, namely, the motor, is running continually. The conditions in this respect are very different from those existing in the case of an intermittently operated driving element, such for example as a steam engine 125 130

which is started and stopped accordingly as it is desired to rotate the drum or allow it to come to rest.

I do not limit myself to the construction 5 herein described and illustrated, except as I may do so in the claims, but I include within the scope of my invention any equivalent mechanisms operating in equivalent manners to produce equivalent results.

10 I claim:

In a hoist, the combination with a stationary framework, of oppositely disposed sets of bearing journals carried thereby, transversely extending shafts mounted in said 15 journals and free to rotate in them, a main gear mounted on each shaft between the bearings thereof and adjacent to the corresponding bearing, a winding drum mounted free to rotate on each shaft between the 20 main gear thereof and the opposite bearing, a friction clutch device between each hoisting drum and the corresponding main gear, shifting mechanism mounted on each shaft between the corresponding drum and bearing away from the main gears, a jack shaft 25

journaled in the frame work and lying parallel to the aforementioned shafts, a pinion on one end of said jack shaft meshing with both of the main gears, a sprocket on the other end of the jack shaft and lying substantially in the plane of the aforementioned shifting mechanisms, a motor secured to the framework and mounted to one side of the hoisting drums, a driving sprocket 30 on said motor lying in line with the sprocket 35 on the jack shaft, and a chain connecting both of the sprockets together and extending between the end of one drum and the framework, and beneath the shifting mechanism of the said drum, whereby the entire power 40 is transmitted from the chain through the entire length of the jack shaft to the pinion thereon, and whereby the elasticity of the entire length of the jack shaft is available for the absorption of shocks and the like.

WENDELL A. BARKER.
